CLAIM

We claim the ornamental design for a glove, as shown and described.

DESCRIPTION

FIG. 1 is a front top perspective view of a glove of the present disclosure;

FIG. 2 is a rear top perspective view thereof;

FIG. 3 is a top plan view thereof;

FIG. 4 is a bottom plan view thereof;

FIG. 5 is a first side elevation view thereof;

FIG. 6 is a second side elevation view thereof;

FIG. 7 is another front top perspective view thereof; and,

FIG. 8 is another rear top perspective view thereof.

The broken lines depict portions of the article that form no part of the claimed design.

1 Claim, 6 Drawing Sheets(56)
